GEORGE B. WILSON AND KARL C. EAGLEY, OF ERIE, PENNSYLVANIA, ASSIGNORS TO SERVICE MANUFACTURING COMPANY, OF ERIE, PENNSYLVANIA, A CORPORATION OF DELAWARE.

LUBRICATING GUN.

Application filed October 8, 1927. Serial No. 224,819.

The present invention is designed to improve grease guns, particularly in the manner of operating the same. In carrying out the invention we provide a pneumatic means which not only forces the grease forward but also affects the measuring of the charge. The invention also contemplates a simple and efficient means for re-loading the gun. Other features and details will appear more fully from the specification and claims.

A preferred embodiment of the invention is illustrated in the accompanying drawings as follows:—

Fig. 1 shows a central section of the gun. Fig. 2 a similar view of the charging end of the grease gun showing the parts in the position assumed after measuring a charge.

Fig. 3 a section on the line 3—3 in Fig. 1. 1 marks the gun cylinder, 2 the charging nozzle. This is secured to the cylinder 1 by a flanged coupling 3 and the discharge end of the nozzle is provided with a screw thread 4 by which it may be attached to a bearing, or to a fitting adapting it for connection with 20 a bearing. A cap 5 is arranged on the rear end of the cylinder 1. The cap has an air supply passage 6. A valve 7 extends from the air supply passage 6 to a T 8. The T 8 has a supply hose 9 leading into it. The valve 7 30 is what is commonly known as a three-way valve provided with a plug 10 having a through-way 11 and a cross-way 12. A valve body has a through-way 13 and an exhaust-way 14. As shown in Fig. 3 the supply is 35 turned in through the valve. With the way 12 turned into register with the passage 13 the way 11 with the passage 14 the upper end of the cylinder may be exhausted.

A pipe 15 extends from the T 8 through a 40 handle section 16 to the charge controlling valve 17. This valve has a body 18. A valve 19 operates on a seat 20 on the body controlling a passage 21. The passage 21 is connected by a radial passage 22 with a passage 23, the passage 23 leading to the lower end of a charging cylinder chamber 24. The valve 19 has a stem 25 which extends through the passage 21 and is provided at its outer end with a head 26 on the underside of which 45 is arranged a valve 27 operating on a seat 28 at the outer end of the passage 21. By pressing in on the head 26 the valve 19 is opened and the valve 27 closed, the opening of the valve 19 permitting pressure to enter the

charging plunger chamber 24 and releasing 55 the head, opening the valve 27 exhausting this cylinder.

The plunger 29 is arranged in the rear end of the cylinder 1. It has the oppositely faced 60 cups 30.

A spring 31 operates on the plunger 29, the front end of the spring being seated on a plunger 32. The plunger 32 is provided with cup 33 and is provided with a spacing block 34 immediately under the cup 33. A charging 65 plunger 35 is arranged on the spacing block 34 and is of greater area than the plunger 32 and operates in the charging cylinder chamber 24. It is provided with a cup 36. A vent opening 37 is provided in the flanged coupling 3 for venting the space behind the plunger 35.

A charge forming cylinder 38 extends from the chamber 24 and a charge forming plunger 39 operates in the cylinder 38. The plunger 75 39 is in the form of a sleeve and the upper end of it is screw-threaded and extends through the plungers 32 and 35 securing these with a spacer block together. A check valve 41 operates on a seat 42 at the lower end of the 80 plunger 39. The valve is provided with a stem 43 which extends through the plunger and terminates with a cross bar 44 which forms a stop limiting the opening movement of the valve. A small ball check 45 operates 85 on a seat 46. This is provided with a spring 47, the pressure on the spring being great enough to close the check against the ordinary air pressure delivered to the gun.

The operation of the gun in delivering 90 charges of grease is as follows:—With the gun full of grease and air on the supply pipe 9, air is turned through the valve 7 into the upper end of the cylinder putting the grease under pressure. When it is desired to deliver a charge of grease through the nozzle, the valve 19 is opened, thus closing the valve 26. The air under pressure is delivered into the charging plunger chamber and this operating on the plunger 35, which is of greater 95 area than the plunger 32, forces the plunger 32 upwardly, thus forcing the plunger 29 rearwardly slightly against the air pressure 9. The upward movement of the plunger 35 carries with it the plunger 39 and the void 100 formed in the space under the plunger 39 is immediately filled by a passage of grease through the plunger 39 past the check valve

41 into this space. The head 26 is then released, thus closing the valve 19 and opening the valve 27. The air is exhausted under the plunger 35 and the pressure acting through the grease on the plunger 32 forces the charge forming plunger 39 forward, the initial movement of this forward operation resulting in the closing of the check valve 41 and the grease in the cavity between the check valve 41 and 45 is then subjected to a pressure equal to the air pressure acting on the entire area of the plunger 32 through the grease and plunger 29. This is readily sufficient to open the check valve 45 and the charge of grease is forced forward through the nozzle with a pressure having the relation of the areas of the charge forming plunger 39 and the plunger 29 and the air pressure which, as shown, would ordinarily be very large and 20 may be made as great as is desirable. A stop 50 is provided limiting the forward movement of the plunger 29.

In order to fill the gun the following mechanism is provided: A filling fitting 48 is secured to the front end of the cylinder 1. The filling fitting 48 is arranged in the cylinder opposite the stop 50 and is closed with a cap 49. By removing this cap a flexible connection, or other device, may be connected to the fitting 48 and lead from a supply of grease. With the plunger 29 forced to the stop 50 and the spring 31 compressed the connection through the fitting 48 is made to a grease supply and upon the release of the air pressure from above the piston 29 the spring acting on this piston tends to form a vacuum in the cylinder 1 and the air pressure operating on the outside supply of grease forces it into the cylinder, thus forming a convenient means 30 for filling the cylinder.

What is claimed as new is:—

1. In a lubricating gun, the combination of a grease cylinder; a discharge nozzle on the cylinder; a forcing plunger in the cylinder; an air connection back of the plunger supplying fluid pressure on the plunger for forcing grease in front of the plunger toward the nozzle; an air actuated means forming measured charges at the nozzle; and devices receiving pressure from the plunger for ejecting the charge.

2. In a lubricating gun, the combination of a grease cylinder; a discharge nozzle on the cylinder; a forcing plunger in the cylinder; an air connection back of the plunger supplying fluid pressure on the plunger for forcing grease in front of the plunger toward the nozzle; a charging plunger opposing the forcing plunger, said charging plunger being of larger area than the forcing plunger; an air supply means delivering air in front of the charging plunger to force a return movement of the charging plunger; and a charge forming device actuated by the charging plunger for drawing in a charge and ejecting said

charge as the air is released from the charging plunger.

3. In a lubricating gun, the combination of a grease cylinder; a discharge nozzle on the cylinder; a forcing plunger in the cylinder; an air connection back of the plunger supplying fluid pressure on the plunger for forcing grease in front of the plunger toward the nozzle; a charging plunger opposing the forcing plunger, said charging plunger being of larger area than the forcing plunger; an air supply means delivering air in front of the charging plunger to force a return movement of the charging plunger, comprising a supply and exhaust valve operating alternately; and a charge forming device actuated by the charging plunger for drawing in a charge and ejecting said charge as the air is released from the charging plunger.

4. In a lubricating gun, the combination of a grease cylinder; a discharge nozzle on the cylinder; a forcing plunger in the cylinder; an air connection back of the plunger supplying fluid pressure on the plunger for forcing grease in front of the plunger toward the nozzle; a charging plunger opposing the forcing plunger, said charging plunger being of larger area than the forcing plunger; an air supply means delivering air in front of the charging plunger to force a return movement of the charging plunger comprising a supply and exhaust valve operating alternately having a passage with opposing seats; a supply valve on one seat, an exhaust valve on the other seat, and a connection between said valves; and a charge forming device actuated by the charging plunger for drawing in a charge and ejecting said charge as the air is released from the charging plunger.

5. In a lubricating gun, the combination of a grease cylinder; a forcing plunger in the cylinder; an air connection leading to the cylinder back of the forcing plunger; an enlarged charging chamber connected with the cylinder; a charging plunger of greater area than the forcing plunger opposing the same; an air connection in front of the charging plunger; a valve for supplying and exhausting air in front of the charging plunger; a charge forming plunger operated by the charging plunger, said charge forming plunger being hollow and forming a passage for grease; a check valve in the charge forming plunger; and a check valve in the nozzle opposing the check valve on the charge forming plunger.

6. In a lubricating gun, the combination of a grease cylinder; a forcing plunger in the cylinder; an air connection leading to the cylinder back of the forcing plunger; an enlarged charging chamber connected with the cylinder; a charging plunger of greater area than the forcing plunger opposing the same; an air connection in front of the charging plunger; a valve for supplying and exhaust-

ing air in front of the charging plunger; a
charge forming plunger operated by the char-
ing plunger, said charge forming plunger
being hollow and forming a passage for
5 grease; a check valve in the charge forming
plunger; a check valve in the nozzle opposing
the check valve on the charge forming plung-

er; and means for loading the last-mentioned
check valve to resist a direct pressure equal
to the air supply pressure. ¹⁰

In testimony whereof we have hereunto set
our hands.

GEORGE B. WILSON.
KARL C. EAGLEY.
